ATTORNEYS.

UNITED STATES PATENT OFFICE.

GEORGE A. BAZÉ, OF HAVANA, CUBA.

MACHINE FOR SHREDDING SUGAR-CANE.

SPECIFICATION forming part of Letters Patent No. 247,874, dated October 4, 1881.

Application filed July 6, 1881. (No model.)

To all whom it may concern:

Be it known that I, GEORGE A. BAZÉ, of Havana, Cuba, have invented a new and Improved Machine for Shredding Sugar-Cane, of 5 which the following is a full, clear, and exact description.

The object of this invention is to more thoroughly tear apart and separate the fibers of cane preparatory to extracting the juices and 10 sugar therefrom.

The invention consists of a horizontal drum having series of knives fixed radially upon it, and provided with blunt edges, revolving within a cylinder, in the top of which is a longitudinal opening for the introduction of the cane, and in the sides and bottom of which are series of radially-adjustable blades, between which the knives on the drum move when the machine is in operation, whereby the cane is torn 15 and shredded to the condition best adapted for the extraction of its juices.

In the accompanying drawings, Figure 1 is a plan of the device partly in section, and with parts broken away to exhibit other parts. Fig. 25 2 is a vertical section of the same on line *x x*, Fig. 1.

Similar letters of reference indicate corresponding parts.

In the drawings, A represents the frame of 30 the device, supporting the cylinder B, which latter is surmounted by a hopper, C, extending its entire length over an opening, B', made in the top of said cylinder B, and in the bottom of said hopper C are secured transverse 35 parallel bars, forming a grating, N, which is fixed at an angle or slope shown, so that the knives *b b*, as they revolve, shall pass between said grating-bars and easily hook over and break down the cane that is fed athwart said 40 grating N. Along the sides and bottom of said cylinder B are secured, in this instance three, boxes, D D D, though their number may be increased or diminished, that open into said cylinder B, and contain blocks E, extending 45 their whole length, and carrying blades *a*, pointing inward to a common center—the drum G. Said blocks E are adjustable to and from the said drum G by means of the screws F, that are passed through the centers of the boxes D 50 D through screw-threaded holes *g*, and have

their enlarged ends entered into sockets *h* in the centers of said blocks E, and revolvably held therein by plates *k*, fixed over said sockets *h*, and said blocks E are steadied in their movements by cross bars or braces O, fixed on the heads of the screws F, at right angles thereto, and having guide-pins O' projecting inward from their ends, parallel with screw F, and entering corresponding guide-sleeves, D', which project outward from said boxes D. The said screws F are turned, and the blocks E thereby 55 adjusted in and out, by means of the screw cross-handles F'.

The drum G is fixed longitudinally in the cylinder B on a shaft, G', that is journaled in 60 the ends of said cylinder B. Secured on the drum G are series of flat knife-plates, S, each having three curved knives or teeth, *b*, forming part of the plate, arranged side by side on the said drum G in such a manner that the 65 said knives *b b* form three separate spirals about said drum G and extend between or intermesh with the knives *a a* of the blocks E, and up between the bars of the grating N. The knives have square or blunt edges and tear or shred, 70 but do not cut, while the grating prevents the cane from crowding into the machine and clogging the knives. It will thus be perceived 75 that the grating N operates to regulate the feed. Discharge-pipes M, through which the shredded cane is ejected from the cylinder B, are located in convenient positions on sides and ends of said cylinder B, as indicated in the drawings.

The shaft G' is extended outward at one end, 80 and carries on it a cog-wheel, H, into which gears a corresponding wheel, I, on the driving-shaft K, which shaft K is moved by the pulley L; or the device may be operated by power applied in any other convenient manner.

It is not designed that the blades *a a* shall be sharp, it being the purpose to shred or pull apart the fibers of the cane rather than to cut them. The drum G being put in revolution, the cane is fed into the hopper C lengthwise on the grating N, and the knives *b b*, reaching up between the bars of said grating N, engage over the cane and break it down through said grating N into the cylinder B, where the cane is then subjected to the action of the knives and 95 100

blades *a b* until it is thoroughly torn and shredded and passed out by the action of the knives *b b* through the discharge-pipes *M*.

I do not confine myself to the precise construction of the machine as herein shown and described, proposing in some cases to increase the number of sets of adjustable knives, and to make certain other modifications, without departing from my invention.

10 Having thus described my invention, what I claim as new, and desire to secure by Letters Patent, is—

1. A cane-shredding machine consisting of

a cylinder containing fixed adjustable blades, a revolving drum provided with curved blades, 15 and a hopper containing an inclined grating, through which the revolving blades project, as described.

2. In a cane-shredding machine, the combination, with the revolving curved knives *b b*, of 20 the inclined grating *N*, as and for the purpose specified.

GEORGE A. BAZÉ.
